DELAYED DIODE CIRCUIT

Dudley E. Foster, Morristown, N. J., assignor to
 Radio Corporation of America, a corporation of
 Delaware

Application December 3, 1936, Serial No. 113,976

1 Claim. (Cl. 250—20)

My present invention relates to diode circuits for radio receiving circuits, and more particularly to an improved type of delayed diode rectification circuit for a radio receiver.

5 One of the main objects of my present invention is to provide a diode rectification circuit for a radio receiver which is of the delayed type, and the delay bias is derived from the space current of a signal transmission tube preceding the diode rectifier.

Another important object of the invention is to provide a delayed AVC network for a receiver, wherein the delay bias for the AVC rectifier is derived from the space current of a signal amplifier controlled by the AVC circuit.

Still another object of the invention is to provide a receiver employing a diode rectifier to provide AVC bias for one, or more, preceding signal amplifiers, and a delay bias being impressed upon the diode electrodes in the absence of signal energy above a predetermined amplitude, the delay bias being derived from direct current voltage developed by space current flow through a resistor disposed in the space current path of one of the 20 signal amplifiers controlled by the AVC circuit.

Other objects of the invention are to improve generally the efficiency and simplicity of delayed AVC circuits for radio receivers, and more especially to provide a receiver which includes a delayed diode AVC circuit which is economically manufactured and assembled in a receiver.

The novel features which I believe to be characteristic of my invention are set forth in particularity in the appended claim; the invention 35 itself, however, as to both its organization and method of operation will best be understood by reference to the following description taken in connection with the drawing in which I have indicated diagrammatically a circuit organization 40 whereby my invention may be carried into effect.

Referring to the accompanying drawing, there is shown that portion of a receiving system which is necessary to a proper understanding of the present invention. The receiving system is shown 45 as of the superheterodyne type, since such type of receiver is in wide use at the present time for radio reception. The second detector tube 1 is of the diode type, and between its anode 2 and cathode 3 is connected a resonant input circuit 4 which is tuned to the operating I. F. The latter may have any frequency value chosen from a range of 75 to 465 kc., and the low alternating potential side thereof is connected to the cathode 3 by means of an I. F. by-pass condenser 5. The 50 load resistor 6 of the detector circuit is connected

to ground from the low alternating potential side of input circuit 4, and there is developed across resistor 6 an audio frequency voltage and a direct current voltage. The audio frequency voltage is impressed upon the input circuit of the 5 audio frequency amplifier network through a condenser 7, and it will be understood that one, or more, tubes may be used in the audio amplifier. A final reproducer will be provided to reproduce the amplified audio voltage.

The direct current voltage developed across the load resistor 6 is employed as the AVC bias, and is transmitted through the direct current connection 8, designated as "AVC", to the signal grid of one, or more, of the preceding signal amplifiers. In order to preserve simplicity of disclosure only the circuit details of the I. F. amplifier stage preceding the second detector are shown. The preceding I. F. amplifier stage includes a tube 9, of the pentode type, between whose input electrodes is connected the resonant input circuit 10 which is tuned to the operating I. F. The cathode of tube 9 is connected to ground through the signal grid bias resistor R₁, the latter being shunted by the I. F. by-pass condenser 11. The plate circuit of amplifier 9 includes the resonant output circuit 12 tuned to the operating I. F., and which latter circuit is magnetically coupled to the input circuit 20 of the second detector.

The input circuit 10 of I. F. amplifier tube 9 is coupled to a preceding I. F. tuned circuit 10', and it is to be understood that the latter may be disposed in the plate circuit of a preceding I. F. amplifier; or it may be disposed in the plate circuit of the preceding first detector stage. In any case, it will be understood that the circuits preceding the amplifier tube 9 may comprise the customary signal collector, followed by one, or more, stages of tunable radio frequency amplification, and the amplified signals being fed to the tunable first detector. Of course, a tunable local oscillator will be provided to feed local oscillations to the first detector; the local oscillations differing at all times from the signals impressed on the first detector by the operating I. F. These circuit details are too well known to those skilled in the art to require any further explanation.

The AVC connection 8 is connected to the low alternating potential side of the input circuit 10 of the I. F. amplifier tube 9, and the numeral 20 designates the usual filter resistor inserted in the AVC connection to suppress pulsating components in the AVC voltage. The grid side of filter resistor 20 is connected to ground through a condenser 21, and the network 20—21 may be given 55

a time constant such that carrier fading will be readily compensated. The cathode side of bias resistor R_1 is connected by the lead 36 to the cathode 3 of diode 1. It will, therefore, be seen that the direct current path between the anode 2 and cathode 3 of diode 1 includes the coil of input circuit 4, load resistor 6, bias resistor R_1 , and lead 36; these enumerated elements being in series between the diode electrodes.

10 Since the anode 2 is connected to the ground side of bias resistor R_1 , it will have a normal negative potential with respect to cathode 3 in the absence of signals whose amplitude does not exceed the voltage developed across resistor R_1 .
15 Further, since the delay bias for the diode 1 is taken from the I. F. amplifier tube 9 which is controlled in gain by the AVC action of the diode rectifier, it follows that the delay bias will decrease in proportion to increase of signal carrier amplitude. As the received signal carrier amplitude increases the AVC action will commence. When the signal carrier amplitude exceeds the delay bias developed across resistor R_1 , the space current flow of amplifier tube 9 is still further decreased. Until the AVC action starts the delay bias has a fixed, predetermined value which is 25 the voltage drop across resistor R_1 .

As the signal carrier amplitude increases beyond that value required to start the AVC action, 30 there is a progressive decrease in the voltage drop across resistor R_1 . In other words in the absence of received signals the diode 1 is biased to prevent detection. Hence, there is no AVC bias developed across load resistor 6, and the delay bias of diode 1 is the full voltage developed 35 across resistor R_1 . As the signal carrier amplitude increases up to the predetermined carrier amplitude at which AVC action is to commence, there occurs a gradual decrease in the delay bias because of peak rectification by diode 1. When the predetermined carrier amplitude has been exceeded, then the AVC action causes such a 40 decrease in the voltage across resistor R_1 that the diode 1 is fully operative to detect and has no 45 delay bias impressed thereon.

This circuit arrangement increases the maximum AVC available by the amount of the delay, and where the delay is applied to the audio detector it eventually removes the delay and consequent possible distortion at high modulation depths. Of course after the predetermined signal carrier amplitude has been exceeded, then the AVC action is normal in the sense that the AVC bias increases proportionately with carrier amplitude. It is to be understood that while the 10 delay bias is shown as being derived from a signal amplifier immediately preceding the AVC rectifier, the bias may also be taken from any other tube whose gain is regulated by the AVC circuit. Furthermore, it is to be understood that the 15 delay bias may be applied to a diode rectifier which functions solely as an AVC bias source, and does not provide audio signals for the audio network.

While I have indicated and described a system 20 for carrying my invention into effect, it will be apparent to one skilled in the art that my invention is by no means limited to the particular organization shown and described, but that many modifications may be made without departing 25 from the scope of my invention as set forth in the appended claim.

What I claim is:

In combination with a diode rectifier having a tuned input circuit and a load resistor for developing a direct current voltage from rectified signal energy, a signal amplifier feeding signals to said diode input circuit, a bias resistor in the cathode circuit of said amplifier for developing a direct current voltage which varies in magnitude 30 with the space current intensity of the amplifier, means for impressing the voltage across the bias resistor between the electrodes of the diode in a sense such as to delay rectification for signals 35 having less than a predetermined amplitude, and means for applying the voltage across the said load resistor to a gain control electrode of said amplifier.
